UNITED STATES PATENT OFFICE.

ARTHUR B. SPERRY, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,393,326.

Specification of Letters Patent. Patented Oct. 11, 1921.

Application filed July 26, 1917. Serial No. 182,967.

To all whom it may concern:

Be it known that I, ARTHUR B. SPERRY, a citizen of the United States, residing at New York, in the county of New York and 5 State of New York, have invented certain new and useful Improvements in Telephone Systems, of which the following is a full, clear, concise, and exact description.

This invention relates to telephone systems, and more particularly to number-indicating devices employed in such systems.

It is the purpose of this invention to provide means controlled from a distant point for indicating to an operator the designation of the wanted line, as well as the designation of the trunk over which the calling line has been extended to the operator's position. Various features will appear from the detailed specification and claims.

20 The drawings, with Figure 1 placed above Fig. 2, diagrammatically represent an A operator's position at one exchange, and a B operator's position at a second exchange. A printing device, shown in Fig. 2, is located at the last-mentioned exchange and is controlled in part by impulses from the sending device at the A operator's position in the first exchange, and in part by an interrupting device located in the second exchange and which is individual to the trunk line.

In the course of the specification reference will be made to a non-numerical switch for connecting an idle printing device to the selected trunk. This non-numerical switch may be of any preferred form, but for the purpose of this disclosure a line switch, of the type disclosed in the patent to Keith No. 1,151,543 of August 24, 1915, is employed.

40 It is believed that the invention will best be understood by describing the method of extending a calling line from the A operator's position to a wanted subscriber's line. Let it be assumed that the A operator has 45 inserted her answering plug into the jack of the calling line and has ascertained in the well-known manner the number of the wanted line. The operator thereupon inserts the plug 5 into the jack 6 of an idle 50 trunk line leading to the distant exchange. A circuit is thereupon completed for energizing the relay 7, which circuit may be traced from grounded battery, winding of relay 7, outer right-hand armature and back 55 contact of relay 8, conductor 9, lower arma-

ture and back contact of relay 10, tip conductor 11 of the selected trunk, tip of jack 6, tip of plug 5, the key spring and its contact 12, right-hand winding of repeating coil 13, to ground. The relay 7 attracts its 60 armature and by so doing closes an energizing circuit for the pull-down winding of relay 8 from grounded battery, left-hand winding of relay 8, armature and contact of relay 7, to ground. The relay 8 attracts its 65 armatures and its left-hand armature causes the plunger 14 of the line switch to connect an idle printing device at the B operator's position with the selected trunk leading from the A operator's position. When the 70 plunger 14 is operated to bring the various contact springs which it controls into engagement, a holding circuit for the relay 8 is closed from grounded battery, right-hand winding of relay 8, contact springs 23 and 75 24, conductor 25, inner right-hand back contact and armature of relay 200, winding of relay 201, to ground. Relay 201 attracts its armatures and a circuit is completed from ground at the left armature of this relay, 80 spring 271, right-hand windings of relays 204 and 205 to grounded battery. The relays 204 and 205 are differentially wound and the right-hand windings of these relays are so wound that in response to current of 85 one direction relay 204 is operated and relay 205 is inert, while in response to current of a reverse direction relay 205 is actuated and relay 204 is inert. The relay 8 is thus energized in series with relay 201 and 90 maintains the plunger 14 in operated position. Springs 26 and 27 when brought into engagement close a break point in the conductor leading from the tip conductor 11, and the springs 28 and 29 are similarly 95 brought into engagement to close a break point in the conductor leading to the ring conductor of the selected trunk, which conductors in series form a signaling circuit leading from the A operator's position to 100 the printing device.

The operator, after depressing key 22 to connect an idle sending device to the cord circuit taken for use, manipulates her sending device to transmit various series of impulses corresponding to the designation of the wanted subscriber's line. The sending device may be of any type in which impulse springs 15 and 16 are separated to transmit a series of impulses, at the close of which 110

series, springs 17 and 18 are brought into engagement when the finger of the operator engages a stop or trigger. As will be seen from a further description of the operation 5 of the sending device, the engagement of the trigger springs 17 and 18 operates to reverse the direction of the current flow in the signaling circuit to control the changeover operations of the printing device.

- 10 Let it be assumed that the number of the wanted line is No. 2579, party R, and that the trunk selected for use is No. 15. To indicate this number at the B operator's position, the A operator actuates her sending 15 device to cause two interruptions in the signaling circuit at the impulse springs 15 and 16. The signaling circuit in which these interruptions take place extends from grounded battery, winding of relay 19, impulse 20 springs 16 and 15, right-hand armature and back contact of relay 20, contact 21 and spring of the key 22, tip of the plug 5, tip of jack 6, tip conductor 11, armature and back contact of relay 31, contact springs 26 25 and 27, conductor 203, left-hand winding of relay 204, left-hand winding of relay 205, conductor 206, contact springs 29 and 28, left-hand armature and back contact of relay 31, ring conductor 30, ring contact of 30 jack 6, ring contact of plug 5, contact 33 of key 22, left-hand armature and back contact of relay 20, to ground. In response to each opening of the contact springs 15 and 16 for transmitting the digit 2, the relay 205, 35 which is responsive to current in one direction vibrates its armature to close an energizing circuit for stepping magnet 207 of the printing device. This circuit is traceable from grounded battery, winding of relay 40 207, conductor 208, winding of slow-release relay 209, armature and contact of relay 205, armature and back contact of relay 204, spring 271, left-hand armature and front contact of relay 201, to ground. In response 45 to each of these impulses, the stepping magnet 207 attracts its armature, causing the pawl 208' to engage the ratchet wheel 281 to rotate the shaft 210 and type wheel 211 carried thereby. When the operator closes 50 the trigger springs 17 and 18 after transmitting the two impulses of the first digit, the relay 20 is energized over a circuit completed from grounded battery, winding of this relay, trigger springs 17 and 18 to ground. 55 The relay 20 attracts its armatures and by so doing reverses the direction of current flowing in the signaling circuit, previously described. In response to this impulse, the relay 204 is actuated, while the relay 205 60 remains inert. When relay 204 attracts its armature it closes a circuit from ground, left-hand armature and front contact of relay 201, spring 271, armature and front contact of relay 204, left-hand armature and 65 back contact of relay 212, winding of relay

213 to grounded battery. Relay 213 attracts its armatures and at its left-hand armature closes a locking circuit for itself from battery in series with relay 212, back contact and armature of relay 214, spring 70 271, left-hand armature and front contact of relay 201, to ground. The relay 204 also maintains its armature actuated for an interval of time sufficient to permit the slow-releasing relay 209 to deenergize, which relay at its armature and back contact closes an operating circuit for the printing magnet 215. This circuit may be traced from grounded battery, winding of relay 215, conductor 216, left-hand back contact and 80 armature of relay 217, springs 218 and 219, which are brought into engagement as soon as the shaft 210 has rotated from its normal position, conductor 220, back contact and armature of relay 209, spring 271, left-hand 85 front contact of relay 201, to ground. The printing magnet 215 attracts its armature, and by means of the arm 221 carried by its armature, brings the paper tape 222 into engagement with the positioned type wheel 90 to print the first digit. The armature of the printing magnet 215 when attracted allows the springs 223 and 224 to come into engagement, thereby completing a circuit from ground through conductor 225, winding of relay 217, to grounded battery, and in parallel through the right-hand contact and armature of relay 213, winding of relay 214, to grounded battery. The relays 214 and 217 attract their armatures and the 95 relay 214 at its armature and back contact interrupts the holding circuit of the relays 212 and 213. The relay 217 in attracting its armatures closes a locking circuit for itself from grounded battery, left-hand front contact and armature of this relay, off-normal springs 218 and 219, conductor 220, back contact and armature of relay 209, spring 271, left-hand armature and front contact 100 of relay 201, to ground. At the right-hand armature of relay 217 an interrupting circuit is completed for the stepping magnet 207 for the purpose of stepping the type wheel 211 to its normal position. This circuit extends from grounded battery, winding of relay 207, contact springs 226 which are opened each time that the magnet 207 attracts its armature, conductor 227, right-hand front contact and armature of relay 217, off-normal springs 218 and 219, to 110 ground over the circuit previously described at the left-hand armature and front contact of relay 201. The stepping magnet 207 continues to actuate its armature and thereby advance the type wheel 211 until this wheel is restored to its normal position, at which time a projection 228 carried by the shaft 210 opens the off-normal contact springs 218 and 219 and closes the springs 229 and 230. This operation is repeated for each of the 115 120 125 130

5 digits 5, 7 and 9. Since the desired line is a party line, it is necessary to indicate to the B operator the designation of the wanted station. This indication is also controlled from the A operator's position.

For controlling the printing of the station's designation, the operator first depresses the key 32 once. This action together with the closure of the trigger springs 17 10 and 18 at the close of the units series of impulses, causes the relay 20 to actuate its armatures twice, and thereby twice reverse the direction of current flowing over the signaling circuit. In response to the first reversal of current when the relay 204 attracts 15 its armature, the relay 213 is energized over a circuit closed from grounded battery, winding of this relay, left-hand back contact and armature of relay 212, front contact and armature of relay 204, spring 271, to ground at the left-hand armature and front contact 20 of relay 201. Relay 213 attracts its armatures and at its left-hand armature closes a locking circuit for itself from ground 25 through the winding of relay 212 in series, back contact and armature of relay 214, to ground at the armature of relay 201. In response to the second reversal of current, a circuit is now closed from ground, left- 30 hand armature and front contact of relay 201, spring 271, armature and front contact of relay 204, left-hand armature and front contact of relay 212, right-hand armature and back contact of relay 232, winding of 35 relay 233, to grounded battery. The relay 233 attracts its armature and at its right-hand armature and contact closes a locking circuit for itself from grounded battery through the winding of relay 232 in series, 40 back contact and armature of relay 214, at the left-hand front contact and armature of relay 201, to ground. When the relay 232 attracts its armature it closes a circuit from ground through conductor 250, winding of 45 the type wheel shift magnet 234, to grounded battery. The type wheel shift magnet 234 attracts its armature and by means of an arm 235 carried by this armature, elevates the shaft 210 to bring the letters of the type 50 wheel into operative relation to the paper tape 222. The operator now transmits positive impulses corresponding to the wanted station.

Let it be assumed that it is necessary to 55 transmit three impulses to indicate the station R. Under this assumption the stepping magnet 207 advances the type wheel 211 and the brush arm 280 carried by the brush shaft three steps or positions. At the close of 60 this series of impulses, when the relay 209 deenergizes, the printing magnet 215 is again energized to cause the arm 221 to bring the paper 222 into engagement with the type wheel 211. When the printing magnet 215 65 attracts its armature to print the letter cor-

responding to the desired station and party line, the springs 223 and 224 are brought into engagement to close a circuit from ground through conductor 225, right-hand armature and front contact of relay 213, 70 winding of relay 214, to grounded battery. The relay 214 attracts its armature and interrupts the locking circuit of the relays 212, 213, 232 and 233. The relay 217 is again energized in parallel with relay 214 75 to cause the stepping magnet 207 to return the type-wheel 211 to its normal position.

Let it be assumed that the trunk line seized for connecting the A operator's position with the B operator's position is known as the 80 No. 15 trunk. Under this assumption it is necessary to cause the type wheel 211 to be rotated once and later five times in order to indicate to the B operator the trunk line over which the call is to be extended. At the 85 B operator's position there is provided an interrupting device, generally designated 33. This interrupting device is individual to each trunk line and comprises a constantly rotating shaft 34 on which there is mounted 90 a cam 36 with which an arm 37 engages to control the operation of the springs 38 and 39. The cam 36 is provided with an insulated projection 64 which closes contact 65 to cause the energization of the left-hand 95 winding of relay 31. The relay 31 controls the connection of the interrupting device 33 to the signaling circuit, including the windings of relays 204 and 205. The relay 31 attracts its armatures only when both of 100 its windings are simultaneously energized, but when energized the right-hand winding is sufficient to maintain its armatures attracted. This insures the timely transmission of the impulses designating the trunk 105 seized, and also insures that the interrupting device is connected to the signaling circuit at the beginning of the series of impulses.

It will be remembered that during the transmission of the station's impulses the 110 relay 232 was energized, and when the springs 223 and 224 are brought into engagement at the time that the station's designation is being printed, a circuit is completed from grounded battery, right-hand 115 winding of relay 31, contact springs 40 and 41, conductor 42, inner left-hand armature and front contact of relay 232, conductor 225, contact springs 223 and 224, to ground. It should be noted that the relay 43 of Fig. 120 1 and relay 237 of Fig. 2 are energized over a circuit in parallel with the right-hand winding of relay 31. The relays 43 and 237 attract their armatures but relay 31 does not attract its armature until its 12 left-hand winding is also energized, which occurs when the insulated projection 64 closes contact 65. When contact 65 is closed a circuit is completed from ground through contact 65 over conductor 45, in- 13

ner right-hand armature and front contact of relay 8, left-hand winding of relay 31, to grounded battery. Since both windings of relay 31 are simultaneously energized, this 5 relay attracts its armatures. As soon as the relay 237 attracted its armature it completed a locking circuit for itself over a circuit traceable from grounded battery, winding of relay 237, its armature and front 10 contact, spring 271, front contact and armature of relay 201 to ground. The relay 237 by attracting its armature applies ground to conductor 42 to maintain the relays 31 and 43 energized. As the arm 37 15 engages the various notches 46 the signaling circuit is closed from grounded battery, lower contact of the spring 38, inner right-hand front contact and armature of relay 31, contact springs 26 and 27, conductor 20 203, left-hand windings of relays 204 and 205, conductor 206, contact springs 29 and 28, left-hand armature and front contact of relay 31, spring 39 and its lower contact, to ground. The relay 205 attracts its armatures 25 once for each closure of the above traced circuit. The stepping magnet 207 is then operated over the stepping circuit previously described, to position the type wheel 211 to print the numeral 1 on the tape 222. 30 After one impulse has been transmitted, the arm 37 engages the projection 47 on cam 36 to reverse the direction of the flow of current over the signaling circuit. In response to this operation the relay 205 re- 35 mains inert. In response to the actuation of the armature of relay 204, the relay 213 is energized and in turn the relay 212, as described. The relay 213 attracts its armature, and when the springs 223 and 224 are 40 brought into engagement by the operation of the printing magnet, the relay 214 attracts its armature to interrupt the holding circuit for relays 212 and 213. The relay 217, which energizes in parallel with relay 45 214, controls the stepping magnet 207 to bring about the restoration of the type wheel to its normal position. The arm 37 of the impulse transmitting device then engages notches 44 of the cam 36 to transmit five 50 impulses. These impulses control the printing device in the manner above described. These impulses operate the printing device to print the numeral 5 on the tape 222, and when the arm 37 engages the projections 70 55 three impulses of opposite polarity are transmitted over the signaling circuit. In response to these three last mentioned impulses, the relay 204 attracts its armature and relay 205 remains inert. In response to 60 the first reversal of current relay 213 is energized as described, and then locks itself up in series with the relay 212. Relay 212 attracts its armatures and in response to the second impulse, relay 233 is energized and 65 attracts its armature and thereby completes a locking circuit for itself in series with the relay 232 to ground at the left-hand armature of relay 201. With the relay 232 energized, the relay 200 is operated over a circuit extending from grounded battery, 70 winding of relay 200, right-hand front contact and armature of relay 232, left-hand front contact and armature of relay 212, front contact and armature of relay 204, to ground at the armature of relay 201. The 75 relay 200 when operated closes a locking circuit for itself from grounded battery, through its winding, left-hand armature and spring 271, left-hand front contact and armature of relay 201, to ground. At the 80 inner right-hand armature of relay 200, the relay 201 is maintained energized over a circuit now extending from ground, winding of this relay, inner right-hand armature and front contact of relay 200, right-hand armature and front contact of relay 212, off-normal springs 273 to grounded battery. These springs are closed until the paper tape is rotated and the printed number appears before the operator, at which time the insulated knob 274 opens the contact springs 273. As long as the relays 200 and 201 are energized, the magnet 275 operates to move the tape from behind the type wheel and into such position that it can be readily observed by the operator. The operating circuit for the magnet 275 extends from grounded battery, winding of magnet 275, springs 226, which are open each time the magnet attracts its armature, conductor 277, 100 left-hand armature of relay 200, contact spring 271, left-hand front contact and armature of relay 201, to ground. When the tape 222 has been properly positioned, the insulated projection 274 opens the contact 105 springs 273, with the result that the relay 201 deenergizes. When relay 201 deenergizes, the relays 8, 200, 212, 215, 232 and 233, which were controlled by said relay, are de- 110 energized. The printing device and its controlling circuits, as well as the line switch for seizing an idle printing device, are now in normal condition. 115 At the time relay 31 attracted its armatures the slow-releasing relay 71 is energized over a circuit completed from grounded battery, winding of this relay, outer right-hand front contact and armature of relay 31, to ground, and in parallel with the relay 71, the left-hand winding of relay 72 is simultaneously energized. When the relay 31 deenergizes, after the impulses for printing the trunk designation have been sent, the relay 10 is energized over a circuit traceable from grounded battery, 120 winding of relay 10, front contact and armature of relay 71, outer back contact and armature of relay 31, to ground. The relay 10 attracts its armatures and at its upper armature and front contact closes a cir- 125 130

cuit from grounded battery, winding of relay 60, left-hand winding of repeating coil 73, upper armature and front contact of relay 10, trunk conductor 11, tip contacts of 5 jack 6 and plug 5, contact 12, right-hand winding of repeating coil 13, to ground. The relay 60 attracts its armatures and at its left-hand armature and front contact closes a circuit for maintaining the relays 10 71 and 72 energized.

It will be remembered that when the type wheel 211 was positioned to print the designation of the desired station the arm 280 was advanced three steps to bring it into 15 engagement with contact 237'. At this time

it will be remembered that the relay 43 holds its armatures in an actuated position, with the result that a circuit is completed from grounded battery, winding of relay 50, conductor 20 51, inner armature and front contact of relay 43, conductor 238 lower armature and back contact of relay 239, which at this time is inert, contact 237, brush arm 280, conductor 240, armature and front contact of relay 237, spring 271, left-hand front contact and armature of relay 201, to ground. Relay 50 attracts its armatures preparatory to applying positive ringing 25 current to the selected party line and completes a locking circuit for itself through its right-hand armature. When the B operator inserts the plug 51 into the jack 52 of the desired party line, a circuit is completed from ground, winding of relay 53,

30 sleeve of jack 52, sleeve of plug 51, windings of relays 54, 55, lamp 56, to grounded battery. The relays 53, 54 and 55 are energized and lamp 56 is lighted in this circuit. The relay 54 actuates its armatures 35 to close a break point in the connecting cord circuit. The relay 55 at its inner front contact and armature completes an energizing circuit for the relay 57 from grounded battery, winding of this relay, armature and 40 back contact of relay 58, armature and contact of marginal ringing relay 59, inner front contact and armature of relay 55, right-hand armature and front contact of relay 60, windings of relays 55 and 54, sleeve 45 of plug 51, sleeve of jack 52, winding of relay 53, to ground. The relay 57 attracts its armatures to apply ringing current to the party line over a circuit traceable from positive source of ringing current 61, right- 50 hand winding of relay 59, armature and front contact of relay 50, left-hand back contact and armature of relay 62, lower front contact and armature of relay 57, ring of plug 51, ring of jack 52, through 55 the substation of party R, tip of jack 52, tip of plug 51, contact spring and armature of relay 54, upper armature and front contact of relay 57, left-hand armature and back contact of relay 63, to ground. When 60 the subscriber at station R removes his re-

ceiver from its hook, the marginal relay 59 attracts its armature and the relay 58, which was previously shunted, now attracts its armature and closes a locking circuit for itself from grounded battery, front contact, 70 armature and winding of relay 58, inner front contact and armature of relay 55, right-hand armature and front contact of relay 60, windings of relays 55 and 54, to ground at the relay 53. At this time the 75 relay 57 is short-circuited and retracts its armatures to disconnect the ringing current and to render the connecting cord circuit continuous. Lamp 56 is also shunted at this time.

At the close of the conversation the supervisory relays 78 and 79 inform the A and B operators that they are to disestablish the connection.

In this disclosure a trunk line whose tip 85 and ring conductors are respectively designated 11 and 30 is shown connecting the A and B operators' positions. It will be understood that in practice a plurality of such trunks are employed. It is also within the 90 scope of this invention to employ line switches or other non-numerical switches to select an idle trunk for interconnecting the above mentioned positions. The broken portion of conductors 11 and 30 indicates 95 the point at which these line switches may be inserted.

If for any reason the A operator abandons the call by removing the plug 5 from the jack 6 before sending a complete series of 100 impulses, means are provided for releasing the line switch and for restoring the printing device to its normal condition. This means comprises a fast-acting relay 75, a slow-acting relay 76 and an interrupting 105 device 77. The relays 75 and 76 are energized in parallel through the sleeve conductor of jack 6 and sleeve of plug 5 to ground, as soon as the plug 5 is inserted in jack 6. When this connection is disestablished, the 110 relay 75 immediately deenergizes and retracts its armatures. The relay 76, however, which is slow to release, maintains its armatures attracted for a brief interval after the relay 75 is deenergized. This serves to 115 connect the interrupting device 77 to the signaling circuit above mentioned, with the result that two or more impulses of current of such direction as to effect the release of the line switch and the printing 120 device, are transmitted.

What is claimed is:

1. In a telephone system, an operator's position, an incoming line leading to said position, a plurality of out-going lines leading from said position, an indicating device at said position controllable from a distant point for indicating the designation of a wanted out-going line, and continuously movable means individual to said incoming 130

line for operating said device to indicate the designation of said incoming line.

2. In a telephone system, an operator's position, an incoming line leading to said position, a plurality of out-going lines leading from said position, a printing device selectively controllable from a distant point for indicating the designation of the wanted out-going line, and continuously movable 5 means individual to said incoming line for operating said printing device to indicate the designation of said incoming line.

3. In a telephone system, an operator's position, an incoming line leading to said position, a plurality of out-going lines leading from said position, a printing device selectively controllable over said incoming line for indicating the number of the wanted out-going line, and means for reversing the 10 current flowing over said incoming line to control the operation of said printing device.

4. In a telephone system, a plurality of operators' positions, telephone lines connecting said operators' positions, outgoing lines 15 leading from one of said positions, an indicating device at the last mentioned position and controllable from a second operator's position to indicate the designation of the wanted out-going line, and means beyond 20 the control of said second operator's position and individual to each telephone line and connectable to said indicating device for indicating the designation of the telephone line taken for use.

5. In a telephone system, an A operator's position, a B operator's position, means including a trunk line for interconnecting said positions, a plurality of out-going lines leading from said B operator's position, a 25 device for indicating the designation of a wanted out-going line, and for indicating the designation of said trunk line, means beyond the control of the A operator's position for operating said device to indicate the 30 designation of said trunk line, and means for selectively operating said indicating device to indicate the designation of the wanted outgoing line.

6. In a telephone system, an A operator's 35 position, a B operator's position, means including telephone lines for interconnecting said positions, a plurality of out-going lines leading to said B operator's position, an in-

dicating device at said B operator's position, means operated at a distant point for causing said indicating device to indicate the designation of the wanted out-going line, and means beyond the control of the A operator's position and individual to the telephone line employed in interconnecting said 40 positions for indicating the designation of the last mentioned line.

7. In a telephone system, an A operator's position, a B operator's position, means including telephone lines for interconnecting 45 said positions, a plurality of out-going lines leading from said B operator's position, a printing device at the last mentioned position, means at said A operator's position for directly setting said printing device to 50 print the designation of the wanted out-going line, and means beyond the control of the A operator's position individual to the telephone line employed in interconnecting said positions for printing the designation 55 of the last mentioned line.

8. In a telephone system, an operator's position, an incoming line leading to said position, a plurality of outgoing lines leading from said position, a printing surface at 60 said position, means operable to print the designation of a wanted line upon said surface, means at a distant point for transmitting series of impulses to control the operation of the last named means, means for returning said last named means to normal after each series of impulses, and means individual to said incoming line for operating said last named means to indicate the designation of said incoming line.

9. In a telephone system, an operator's position, an incoming line leading to said position, a plurality of outgoing lines leading from said position, an indicating device at said position controllable from a distant point for indicating the designation of a wanted outgoing line, means for reversing the current flowing over said incoming line whereby to control the operation of said indicating device, and means for operating said device to indicate the designation of said incoming line.

In witness whereof, I hereunto subscribe my name this 20th day of July, A. D., 1917.

ARTHUR B. SPERRY.
